JOHN WILLIAM WEST, OF CAMBERWELL, LONDON, ENGLAND.

BINDING CASE FOR HOLDING SHEET MUSIC AND THE LIKE.

Application filed October 12, 1921. Serial No. 507,269.

To all whom it may concern:

Be it known that I, JOHN WILLIAM WEST, of 9 Bushey Hill Road, Peckham Road, Camberwell, London, S.E. 5, England, a 5 British subject, have invented certain new and useful Improvements in Binding Cases for Holding Sheet Music and the like, of which the following is a specification.

This invention relates to binding-cases, 10 for holding sheet-music and other double-leaf papers, of the kind having a rigid back-member including what is hereinafter referred to as the string-bar, whereof the inner or front surface is of convex and sub- 15 stantially half-round cross-section and is provided at the ends with straining-bridges; a plurality of binding-strings, which extend side-by-side from end to end over said front surface of the string-bar, being 20 stretched over the straining-bridges whereby said binding strings are spaced apart from one another and from the string-bar so as to be each adapted to receive beneath it the back-fold of a double-leaf sheet of 25 paper comprising four pages or any multiple thereof.

The primary object of the present invention is to provide an improved binding-case of the kind referred to, so constructed as to 30 allow any selected paper contained therein to lie flat, without tendency to curl upwards, when the binding-case is laid open so as to expose the particular paper selected.

The invention will be described with reference to the accompanying drawings wherein Figure 1 is an inside face view of the binding-case, portions being broken out; Figure 2 is a transverse section on line 2—2 of Figure 1, drawn to a larger scale; Figure 40 3 is a side elevation, partly in section, of the string-bar, shewn separately to a smaller scale; Figure 4 is a perspective view of one end of the back-bar with the terminal block attached thereto; Figure 5 is a perspective view of one of the terminal blocks; Figure 6 is an end view of the string-bar shewing the attachment of the strings; and Figure 7 is a section on line 7—7 of Figure 2, drawn to a larger scale.

50 The improved binding-case, as seen in the example illustrated, comprises the usual pair of flat boards *a*, *a* forming the rigid

outer covers of the binding-case, these boards being held together at the rear by a hinge-strip *b* of leather or other strong and flexible material whereof the respective margins are cemented at *c*, *c* to the outer rear margins of the boards *a*, *a* (as by paste) so as to leave between the rear edges of the latter a central unattached width of the hinge-strip *b* corresponding to but greater than the distance between the boards *a*, *a* when the binding-case is closed by folding said boards together. A half-round bar *d* of rigid material, preferably wood, herein-after termed the "back-bar", is cemented (as by glue) to the central unattached portion of the width of the hinge-strip *b*, the half-round surface of this back-bar *d* being towards the rear so as to contact with the hinge-strip *b*, whilst the flat inner surface of the bar *d* extends substantially in the common plane of the outer surfaces of the boards *a*, *a* when the binding-case is laid fully open. For the sake of greater security a strip *e* of linen or other strong and flexible material is cemented (as by glue or paste) to the flat inner surface of the back-bar *d*, and also to the edges and rear margins of the boards *a*, *a* as at *f*, *f*, the margins of the strip *e* being preferably afterwards concealed for the most part by the usual lining *g* of paper pasted over the inner surface of each board *a*, *a*.

A half-round bar *h* of rigid material, preferably wood, herein-after termed the "string-bar", is secured (as by glue supplemented if desired by nails as at *i*) to the central portion of the width of the strip *e* where the latter contacts with the back-bar *d*, the half-round surface of this string-bar being towards the front whilst its width is less than that of the back-bar by an amount corresponding with or slightly greater than the conjoint thicknesses of the two boards *a*, *a* so that sufficient space is left beyond each edge of the string-bar to accommodate the corresponding board *a* when the latter is brought to the closed position relatively to the back-bar. Over the half-round surface of the string-bar *h*, at each end thereof, is secured (as by glue) a narrow arcuate straining-bridge *j*, consisting preferably of a rectangular strip of leather, which em-

braces the angular width of the half-round surface and is of such thickness as to up-stand therefrom to a height corresponding approximately to the thickness of the folded 5 sheets of paper which are to be held in the binding-case; whilst over this bridge *j* are stretched side-by-side a number of strings *k* . . . corresponding in number to the number of such folded sheets which the binding- 10 case is adapted to accommodate.

It is usually more convenient to stretch the strings *k* upon the string-bar *h* before the latter is fixed to the back-bar *d*, the preferred manner of stretching and securing 15 the strings being as follows. A recess *l* is formed in each end of the string-bar *h* at the rear thereof, and within this recess is fixed a cleat pin *m* extending lengthwise of the bar and projecting temporarily beyond 20 the extremities thereof. A single length of suitable cord or strong thread is then made fast to the pin *m* at one end, and is passed thence over the bridge *j* at the same end, thence lengthwise of the string-bar *h* near 25 one edge thereof and parallel to the axis of the bar, thence over the bridge *j* at the farther end, and round the adjacent pin *m*; the string being wound or passed in this manner to-and-fro lengthwise of the string- 30 bar as often as required in order to provide the desired number of individual strings *k*, which are tightly stretched close beside and parallel to one another. The use of leather for the bridge *j* ensures the strings *k* biting 35 into the bridge and prevents them from slipping over one another; if a material harder than leather is used, the bridge may be formed with shallow notches to retain the individual strings in place. After the 40 free end of the whole length of string has been made fast, the projecting end portion of each pin *m* is bent over upon the convolutions of string lapped around the pin so that whilst the pin no longer projects 45 beyond the extremity of the string-bar *h*, the strings are firmly clamped to the pin *m* itself where they pass around it.

The back-bar *d* and string-bar *h* are of 50 equal length, whilst the boards *a*, *a* and backing-strip *b* are of such depth as to extend a distance of (say) about half an inch, more or less, beyond each end of the back-bar and string-bar; the terminal space thus 55 left at each end being occupied by a block *n*, preferably of wood, secured to the back-bar *d* by a nail *o* (supplemented by glue if desired) so as to cover the extremities of the bars *d* and *h* and form a finish to the 60 article. Each block *n* is of substantially oval shape so as to conform to the half-round contour of the back-bar *d*, and has at its inner side a projecting portion *p* of substantially crescent shape adapted to fit over and conceal or protect the bridge *j* and the portions of the strings *k* lying thereon. 65

On inspection of Figure 2 it will be readily appreciated that, when the binding-case is laid open on a table or other support, the back-bar *d*, owing to its half-round contour, can roll over laterally in either direction so far as may be necessary to enable any selected paper amongst the contents of the binding-case to be exposed in the flat without tendency to curl upwards. Experience shows that this feature, which is 70 novel, is of the utmost practical value; the absence of the half-round back-bar having for effect to prevent any of the papers, except at most a very few of those in the middle of the collection, from lying open flat. 75 The importance of the feature in question will thus be obvious in the case, for example, of sheet-music.

Again, it will be seen from Figure 7 that the inwardly-projecting portion *p* of each terminal block *n*, by reason of its overlapping the adjacent straining bridge *j*, is adapted to co-operate therewith in preventing, more effectually than have the constructions hitherto proposed, injury to the 80 papers held in the binding-case, owing to such papers tending to slip lengthwise of the binding-strings *k* to a distance beyond the straining-bridge and thus to become torn or split along their back-folds. 85

I claim:—

1. In a binding-case, the combination with the rigid back-member and a string-bar on the back-member and provided with straining bridges at its ends, of a pair of cleat-pins fixed at the respective ends of the string-bar beyond the corresponding straining bridges, and a plurality of binding-strings constituted by successive portions of the length of a single continuous string 100 passed to-and-fro from end to end over the convex surface of the string-bar and repeatedly doubled around each in turn of the respective cleat pins, substantially as set 105 forth.

2. A binding-case as claimed in claim 1, wherein each cleat-pin is fixed in a recess formed at the rear side of the corresponding end of the string-bar between the latter and the front side of the rear-section of the rigid back-member, substantially as set 115 forth.

3. In a binding-case as claimed in claim 2, the combination with the rigid back-member of a pair of terminal blocks mounted thereon and each adapted to constitute both a finish for the corresponding extremity of said back-member and also a closure for the adjacent cleat-pin recess, substantially as set 120 forth.

4. In a binding-case, the combination of a string-bar having straining bridges at its ends, and a rigid back-member provided with terminal blocks, said blocks being provided at their inner sides with projecting 125

portions adapted to overlap the adjacent straining bridges in such manner as to co-operate therewith in preventing papers held in the binding-case from slipping lengthwise of the binding-strings beyond said straining-bridges, substantially as set forth.

5. A binding case comprising a rigid

back, and a plurality of covers hingedly connected thereto, said back comprising a plurality of semi-cylindrical sections of different diameters secured together with their longitudinal axes in coincidence.

JOHN WILLIAM WEST.
